EUGENE F. KLINE, OF LOS ANGELES, CALIFORNIA.

BRICK VENEER AND SYSTEM.

Application filed January 19, 1926. Serial No. 82,179.

This invention relates particularly to a type of building material intended to counterfeit the appearance of brick laid up in a usual manner, and a system of using the same 5 in the construction of buildings.

It is an object of this invention to provide brick veneer in the form of slabs, which may be cast or otherwise formed from, for example, a suitable clay and thereafter 10 "fired" somewhat as brick or terra cotta products are customarily rendered sufficiently rigid and durable for transport and use; and it is an object of my invention to provide brick veneer units suitable for attachment 15 to studs or to equivalent elements of the frames or walls of dwellings or other buildings.

It is an object of this invention to provide brick veneer units which, although comparatively strong, may be so thin that the total expense thereof, to cover a given area, shall be considerably less than the cost of a brick wall of corresponding area; and, in preferred embodiments of my invention, the 25 respective units may be of such size as to permit the convenient handling of the same, by a single workman; and they may be provided with channels or depressions corresponding to the "joints" between superimposed courses 30 of brick, as ordinarily laid,—these channels or depressions being optionally filled with a suitable mortar, or the like, either before or after the units are applied to a wooden frame, or other wall structure.

35 It is a further object of this invention to provide special means and methods for the interfitting, attachment, and reinforcement of units of the general character referred to and for the construction of walls comprising the same.

40 Other objects of my invention may be best appreciated from the following description of alternative embodiments thereof, taken in connection with the appended claim and the 45 accompanying drawings, in which

Fig. 1 is an elevational view, showing, in solid lines, a single unit of one form of my brick veneer, together with portions of studs and portions of a masonry foundation there- 50 below,—the interfitting of adjacent units being indicated by dotted lines, and parts being broken away.

Fig. 2 is a vertical section in a plane such as that indicated by the line 2—2 of Fig. 1.

55 Fig. 3 is a vertical section so taken as to cut through interfitting projecting portions

of adjacent units, somewhat as indicated by the line 3—3 of Fig. 1, but illustrating a slightly modified and thicker form, as secured to an angle-iron stud as hereinafter described.

60 Fig. 4 is an elevational view corresponding to a portion of Fig. 1, near the upper left-hand corner thereof, but with apertured reinforcing or bonding strips inserted in channels or depressions representing joints and not as yet concealed by mortar.

65 Fig. 5 is a detail view, on an enlarged scale, taken substantially as indicated by the line 5—5 of Fig. 4.

70 Fig. 6 is an elevational view showing, in full lines, one form of unit (which may be of the same cross section as that illustrated in Fig. 3) specialized for use adjacent a window or door opening or at a corner,—and 75 suggesting the use of reinforcement in the form of rods inserted in the horizontal depressions (representing joints between pretended courses of bricks) and extending past actual vertical joints between veneer units. 80

Fig. 7 is a detail view, on an enlarged scale taken substantially as indicated by the line 7—7 of Fig. 6.

85 Fig. 8 is an elevational view taken substantially as indicated by the arrow 3 of Fig. 6.

Fig. 9 is a separate perspective view of a 90 veneer corner unit comparable with that shown in Figs. 6 and 8, but in which the respective faces, meeting at an angle of 90° more or less, have substantially the same horizontal extent—amount to about one and one-half times the length of a brick.

Fig. 10 is a vertical section illustrating a 95 form of my invention in which flanged metallic elements in the form of so-called channel irons are used as studs, said studs being used also for the support of an inner wall facing in the form of wire-reinforced plaster.

Fig. 11 is a somewhat diagrammatic view, 100 with parts broken away, showing one preferred type of fireproof frame construction, suitable for use in the manner indicated in Figs. 10, 12 and 13.

Fig. 12 is a detail cross sectional view taken 105 substantially as indicated by the line 12—12 of Fig. 11.

Fig. 13 is a horizontal sectional detail view, taken substantially as indicated by the line 13—13 of Fig. 10.

110 Referring to the details of that specific embodiment of my invention chosen for pur-

poses of illustration, 11 being any suitable foundation, of masonry or other construction, and 12 being studs, or the like, supported thereby, 13 may be a veneer unit illustrating my invention and comprising staggered prominences 14, separated by horizontal channels 15 and vertical channels 16, respectively counterfeiting the customary horizontal and vertical mortar joints between superimposed courses of brick.

As suggested in Fig. 2, instead of forming the back or inner faces 17 of my veneer units entirely parallel with the described front surface (provided with depressions to counterfeit mortar joints) I may make the mentioned rear or inner surface substantially or entirely flat; and, in order to provide for the convenient attachment and interfitting of said units I may provide the same with any desired apertures 18, and I may permit prominences, corresponding in length approximately to half bricks, to extend horizontally from the respective ends of my units; and I may provide a peripheral fin or flange 19, corresponding in thickness and diameter to the webs 20 (at the bottom of the channels or depressions 15 and 16) extending along, for example, the entire upper edge of each unit, and also along the ends of the mentioned laterally projecting half bricks,—as at 21 and 22, Fig. 1.

By positioning the mentioned apertures 18, or their equivalents, only in the connected webs 20 (at the bottoms of the channels or depressions 15 and 16 and/or the projecting flanges 19, 21 and 22) I make it possible to conceal any nails, screws, or the like, used in the attachment of my units and possible also to employ, in connection with or independently of such nails, or the like, any desired reinforcing or auxiliary attaching means adapted to lie within the mentioned depressions.

As best shown in Figs. 4 and 5, I may, for example, provide the units 13 (either before or after a "firing" or other hardening operation) with apertures 18 considerably exceeding in diameter the nails or screws 23 by which the same are to be attached; and, instead of permitting the head 24 of such nails or screws (or the threaded ends of bolts, or other anchoring elements—which may be imbedded in concrete) to contact directly with the webs 20 (at the bottoms of the channels 15 and 16) and/or the projecting fins 19, 21, 22, I may optionally interpose reinforcing means such as apertured strips 25, shown as extending longitudinally of the horizontal channels 15, and/or fibrous or other slightly resilient or yielding washers 26; and it will be accordingly understood that, even if some of the mentioned channels 15, 16 are filled or partially filled with mortar (in order to simulate the appearance of an ordinary brick wall) at the place of original manufacture, or in advance of the delivery or attachment 60 of my units to a building; such parts of hori-

zontal channels 15 as are intended to receive reinforcing or connecting strips 25 and/or nails or screws 23, or the like, are not to be filled with mortar until after said units are secured in their permanent places in a wall. 70

The slabs or units illustrated in Figs. 2, 4 and 5 being comparatively thin, I may resort, at corners and/or at window and/or door openings, to the use of interfitting special blocks of the general character separately 75 illustrated in Fig. 9.

Although the interfitting ends of adjacent units are not necessarily to be disposed opposite studs, some of the holes 18 may naturally be disposed at an interval, such as an interval of sixteen inches, corresponding to the distance between studs, as the same are commonly positioned; and, if desired some or all slabs or units may be provided with extensive series of holes 18, arranged in inclined 80 lines, substantially as suggested in Fig. 1,—in order to provide for the securing of the same to studs spaced at unusual intervals; and/or the composition of my units may be such as to permit of the cutting or driving 85 of holes through the webs 20, at any desired point and at the time of their attachment to wall elements of a building.

Instead of using apertured strips 25 as a means of attaching, reinforcing, and maintaining the alignment of units of the general character described, optionally forming said units in somewhat thicker slabs and optionally omitting peripheral fins or flanges from the interfitting portions thereof, somewhat as suggested in Fig. 3, I may employ, in the general manner suggested in Figs. 6 and 7, means such as mere round or other rods 30, adapted to lie in any horizontal depressions 15^a and to extend across the joints between adjacent blocks 13^a,—said rods being of any desired length and being retained and concealed by, for example, a mortar mixture 31, or its equivalent; and, as suggested in said figures, instead of forming corner units with interfitting projections having rebent or inwardly projecting extensions or terminal portions, I may optionally adapt the integral corner units 18^a to extend entirely around a corner. 100

For the uses last referred to, I may provide corner units of various types (the corner unit shown in Figs. 6 and 8 having an extreme horizontal length on its longer face, equivalent to the length of two and one-half bricks, and an extreme length, on its shorter face, equivalent to one brick) but I illustrate in Fig. 9 what I may refer to as a typical or standard corner unit both of whose faces have the same horizontal extent, corresponding to 105 one and one-half bricks; and, in order to facilitate a staggering of joints, my corner units may, if desired, be made of a standard height different from that of the associated flat or single-plane units; and it may ob- 110

viously be regarded as immaterial whether flanges (such as are shown at 19 in Fig. 1, and at 19' in Fig. 9) be provided exclusively along (say) the top and the right-hand (or the left-hand) lateral edges, or exclusively along the top edge and the protected lateral edges, or (as shown at 19, 21 and 22, Fig. 1, or at 19', 21' and 22' of Fig. 9) along the top edge and the more exposed lateral edges—provided only that some consistent system is employed. The illustrated system enables all units to be secured to any studs or the like, over which even their extreme ends may be made to extend; and although the outside faces of the corner units shown in Figs. 6, 8 and 9 are disposed at right angles, it will be understood that, if and when the call for special corner units is sufficient, provision may be made for an intersection of adjacent faces at various angles. In the case of baked or fired units, wire reinforcements may be dispensed with.

Herein I have stressed the possible use of materials such as brick or terra cotta clay in the formation of my described units; but it should be understood that I may use any desired alternative composition, such as a composition including asbestos fibre and/or Portland cement, or the like; and that reinforcing elements of the general character shown in Fig. 5, may be of any desired cross section or length,—even extending, if desired entirely about a building, above the door and window openings thereof.

My described brick veneer units may be used in conjunction with either wooden or metallic or other frame elements previously positioned by a foundation; and, in Figs. 10-13 inclusive, I illustrate one advantageous type of metallic frame, suitable for use in fireproof construction and providing means for the reliable maintenance of metallic studs in an upright position, means for the securing of a plate, of the same general type, thereabove, means for the providing of door and window openings, and means for the attachment of both the described veneer units and an interior facing to the mentioned metallic studs.

For example, I may imbed in a concrete or other foundation such as is suggested at 11^a, Fig. 6 and 11^b, Fig. 11 a plurality of substantially vertical flange elements, such as angle irons or channel irons 12^b, these being preferably formed either by rolling operations of a known character or by cutting and bending the same from a suitable comparatively heavy sheet metal. Obviously, when desired, diagonals (not shown) may be interposed; but, when the studs are embedded in the indicated manner and are locked together at the tops thereof, as by means of an overlying plate of the general character suggested at 32^a, Fig. 6 and 32^b, Fig. 11, this plate being shown as slightly broader than

the mentioned studs and as comprising not only a horizontal portion but one or more downwardly extending flanges 33^b, adapted to overlie a similar flange or flanges 34^b of the studs 12^b, in the case of one story buildings sufficient rigidity may be obtained without bracing, as by riveting or bolting the described parts together, as at 35^b; and a further strengthening effect may be obtained by the use of a suitable reinforcement and/or compositions in the construction of an inner facing somewhat as suggested at 36^a, Fig. 6 and at 36^b, Fig. 10, subsequently to an attaching of brick veneer blocks 13^b, as by means of bolts or screws 23^b, in the general manner best shown in Figs. 10 and 13.

That is to say, although I may employ studs in the form of T beams or I beams or similar angle or L beams (the use of the latter being suggested at 12^a in Fig. 3) I suggest in Figs. 10-13 inclusive the use of studs in the form of U bars or channel irons, the outer flanges 34^b thereof being apertured, as at 37^b, for use in the attachment of the mentioned brick veneer units 13^b, and either the transversely extending webs 38^b or the inner flanges 39^b being used for the attachment of an inner facing. The mentioned inner wall may be of any preferred construction but, in order to facilitate its attachment subsequently to the tightening of nuts 40^b on the bolts 23^b (when such nuts are employed) I suggest the attachment of a reinforcing material, such as expanded metal or a wire mesh 41^b, by means such as additional bolts 42^b, shown as provided not only with nuts 43^b but with nicked members 44^b, and the subsequent application of a suitable plaster,—preferably a plaster containing a comparatively high percentage of Portland cement, or a like ingredient contributing to the rigidity of the resultant structure.

Although door and window openings may be provided for in any desired manner, I suggest in Figs. 11 and 12 the use, for this purpose, of transverse angle or channel elements 45^b, of such width that, upon cutting the same to suitable length and upturning tongues 46^b at right angles, projecting portions 47^b and 48^b are adapted to overlie and contact with the respective flanges 34^b and 39^b of studs 12^b, means such as bolts or rivets 49^b being employed to hold the mentioned parts in their indicated relationships; and it will be appreciated that a construction of the general character described is especially suitable, whether or not building paper, in one or more layers, is interposed, as at 50^b, for use under unusual climatic conditions, such as conditions of extreme heat or cold, by reason of the provision of an air space, corresponding to the distance between the outer faces of flanges 34^b or 39^b, or their equivalents; and the tieing of all members together, in the described manner, as well as the an-

choring of the same to a foundation, renders this construction also especially appropriate to regions in which architectural problems are complicated by danger of earthquakes or 5 danger of cyclones.

Buildings constructed, as above described, although inexpensive, may be not only attractive in appearance and practically fire-proof, but better adapted than actual brick 10 to withstand earthquakes; and, although I have herein described alternative embodiments of my invention, it will be appreciated not only that various features thereof might be independently employed, but also that 15 numerous additional modifications might be devised, by those skilled in the art to which this case relates, without the slightest departure from the spirit and scope of my in-

vention, as the same is indicated above and in the following claim.

20

I claim as my invention:

In combination with a wall facing supporting means; a wall facing mounted thereon comprising interfitting brick veneer units, having formed on the external surface thereof, bricklike prominences separated by depressions adapted to contain mortar; securing means mounted in said depressions, and reinforcing means comprising rods mounted in said depressions and extending between 25 said interfitting units and adapted to be imbedded in said mortar.

25

In testimony whereof, I have hereunto set my hand at Los Angeles, California, this 7th day of January, 1926.

EUGENE F. KLINE.
